UNITED STATES PATENT OFFICE.

MOSES L. TRIMMER, OF CRAIG, MISSOURI.

ATTACHABLE HOPPER.

Application filed November 20, 1922. Serial No. 602,141.

To all whom it may concern:

Be it known that I, MOSES L. TRIMMER, a citizen of the United States, residing at Craig, in the county of Holt and State of Missouri, have invented certain new and useful Improvements in Attachable Hoppers, of which the following is a specification, reference being had to the accompanying drawings.

10 This invention relates to hoppers and has for its object to provide a hopper capable of being attached to any suitable support for discharging material in the desired receptacle or place.

15 It is another object of the invention to provide a device of this character capable of being suspended not only from the side of a support such as a railroad car or wagon, but spaced from the support so as to permit 20 discharge of the material a considerable distance from the support without danger of waste.

It is also an object of the invention to provide a device of this character having a body 25 member and an inclined bottom and an end member for permitting discharge of the material from the body member, said end member being normally held firmly in position by means also used to open said end mem- 30 ber.

It is a further object of the invention to provide a hopper of this character including brackets for suspending the hopper from the side of a support, and wherein the sus- 35 pending means of the bracket do not receive the entire strain of the load, but are assisted in their supporting action by holding means without interfering with the inclina- 40 tion of the bottom of the hopper.

45 With these and other objects in view, the invention consists in the improved construction and arrangement of parts to be herein- after more particularly described, fully claimed and illustrated in the accompanying drawings, in which:—

Figure 1 is a perspective view of an attachable hopper constructed in accordance with an embodiment of the invention and showing the hopper closed and applied to a 50 support;

Figure 2 is a longitudinal sectional view showing the hopper open; and

Figure 3 is a bottom plan view.

Referring to the drawings, 5 designates a 55 hopper, comprising side members 6 and 7, the upper edge 8 and front edge 9 of each

of the side members being disposed at right angles to each other. The lower edge 10 of each side member is inclined obliquely of the side members and upwardly. The lower edge 10 of each side member inclines in the same direction. The side members are connected at their upper forward ends by a connecting strip 11. Engaged with the lower inclined edges 10 of the side members 6 and 7 is a bottom member 12, said bottom member being inclined so as to substantially provide a chute through the cooperation of the sides 6 and 7. Hinged or otherwise secured to the connecting strip 11 is a closure or end member 13, adapted to close the hopper to retain matter therein until it is desired that the same be discharged.

In order that the hopper may be supported at the place desired, for instance, from the side of a gondola railroad car, there is provided novel supporting means in the form of brackets 14, each bracket comprising a supporting arm 15 having a plurality of openings 15^a provided in one end thereof. Formed integral with the opposite end of the supporting arm 15 is a holding arm 16, said arm being disposed in angular relation to the arm 15. The arm 16 is also provided with a series of openings which extend longitudinally thereof. It is desirable that the brackets be adjustable. To permit this, an extension 17 is provided, one end of said extension having openings adapted to register with certain of the openings 15^a, the opposite end 17^a of the extension being extended in angular relation to the first mentioned end and provided with a series of openings 18 for the reception of a pin 19, said pin being adapted to extend into any one of the openings 18 to accommodate the device to the support with which it is engaged. In order that the arm 16 may be adjustable, there is provided an extension 20, one end of the extension being enlarged to provide a foot 20^a. The opposite end portion of the extension has openings adapted to register with certain of the openings of the arm 16, suitable fastening means, such as bolts, being passed through the registering openings to hold the extension in the desired adjusted position. The foot 20^a is adapted to engage the outer face of the support or car beneath and in spaced relation to the pin 19. The upper or supporting arm 110

is disposed in an inclined position and is secured to the lower face of the bottom 12,

one bracket being disposed on each side of the bottom thereof. It will be noted that the upper edge of the bottom 12 is disposed in spaced relation to the pins so as to permit 5 said upper edge to be disposed in the plane of the upper edge of the support or car. By this means the hopper is suspended from the side of the car and in order that the inclination of the hopper may be maintained, 10 the holding arms are intended to engage the outer face of the car, thus holding the hopper in the desired position and at the same time relieving the extension 17 of the greater portion of the supporting strain without 15 causing injury to the support or car. No fastening means of any description are necessary in order to secure the hooks to the car, as the weight of the hopper, in addition to the holding arms 19, is sufficient to maintain 20 the hopper in the desired position on the support or car.

In order that the closure or end member 13 may be actuated without danger to the operator, and without requiring unnecessary 25 time and labor on the part of the operator, there is provided a novel actuating mechanism comprising a main shaft 21 which is journaled in bearings 22 carried by the side portions of the bottom member 12 adjacent 30 the lower end of the bottom member. The ends 23 of the shaft 21 are extended at right angles to the shaft. The extremities of the ends 23 are extended at right angles to provide pivot pins or trunnions 23^a. Extending 35 from the central portion of the shaft 21 in angular relation to the ends 23 and the shaft, is an actuating lever 24 having an opening 25 in its end for the reception of a cable 26. This cable 26 is intended to extend 40 over a pulley 27 carried by the upper end portion of the bottom member 12. The cable may be of a length sufficient to extend to any point so that if desired the operator may actuate the closing member from 45 within the car.

Secured to each side portion of the closure member 13 is an arm 28, said arm projecting beyond the edge of the closure member and the side portions. A connecting rod 29 50 is provided for connecting the arms 28 to the ends 23 of the shaft. This rod is relatively long and has its end portions disposed slightly in angular relation to each other. The end portion 30 of each of the 55 rods 29 is connected to the adjacent arm 28, while the end portion 31 is connected to the extremity of the adjacent arm 23 by means of the extremity 23^a of the arm 23 which extends through the opening in the end portion 31 of the rod 29.

In view of the angular position of the end portions 30 and 31 of the rod 29, it is possible for the extremity 23^a and the pivot of the rod 29 at the bearing 22 and the pivot 65 of the end portion 30 of the rod to be dis-

posed substantially in alignment or in other words in a dead center so as to lock the end member in its closed position without requiring further fastening means.

The above arrangement permits the hopper 70 to be filled with any material without danger of the end member accidentally opening. After the desired quantity has been placed in the hopper the cable 26 may be pulled so as to break the dead center of the 75 pivots mentioned above, thereby causing movement of the hopper 29 as well as the shaft 21 and swinging the closure member upwardly, thus releasing the contents of the 80 hopper.

In order to cause the closure member to swing to its closed position automatically, there is provided a spring 33, the end 34 of the spring being secured to the lower end portion of the bottom 12, while the end portion 35 of the spring is secured to the end of the actuating lever 24. This spring causes 85 downward movement of the lever 24, thus swinging the closure member downwardly and also causing the pivots above mentioned to be returned to their dead center position, thus locking the closure member.

From the above it will be readily seen that this invention provides a novel form of hopper capable of being positioned on any support capable of receiving the hooks 17 so that its utility is not limited. In addition to this the hopper, regardless of its supporting means, is always positioned so that the bottom 12 is inclined to facilitate discharge of the matter, and after the hopper is lowered it is not necessary to disengage the hopper from the support, but simply operate the actuating mechanism of the closure 13. All of these features are possessed by a device 90 which is simple in construction and compact in form.

What is claimed is:—

1. An attachment hopper comprising spaced side members, a movable end member and an inclined bottom member, brackets carried by each side portion of the bottom, each bracket comprising a supporting arm disposed at an inclination to a support and adapted to be secured to the bottom of the hopper, a holding arm projecting from the lower end portion of the supporting arm, said holding arm extending at right angles to the support, the opposite end of the supporting arm having an adjustable extension, 110 adjustable means carried by said extension for holding the arm in connection with a support, and an adjustable extension carried by the end of the holding arm and arranged to engage the adjacent face of the extension. 115

2. A car unloading chute including an inclined bottom, and supporting brackets carried by said bottom, each of said brackets including an inclined supporting arm fixed to the bottom of the hopper, a depending 120

stop adjustable longitudinally of the upper end of each bracket and adapted to detachably engage over the upper edge of the side of a car, and a holding arm rigid with the 5 supporting arm extending rearwardly from the lower end of the supporting arm and adapted to rest against the outer face of the side of the car for holding the chute positioned with its bottom disposed at an outward and downward inclination.

3. A car unloading hopper chute embodying a bottom, a pair of sides, a cross piece connecting the sides above the bottom, a vertically swinging door depending from and 15 hinged upon said cross piece, a horizontal crank shaft journaled below the bottom and having crank arms at both ends, connecting rods pivotally connected with said crank arms and door, a spring normally holding 20 the door closed, and an additional crank arm on said crank shaft movable whereby to open the door.

4. In combination with a car unloading hopper chute, brackets carried by said chute to detachably attach the latter to the side of a car, said brackets being extensible for adjusting the hopper toward or away from the side of the car, each of said brackets further embodying an intermediate member 25 having an upper inclined portion secured to the bottom of the hopper, and a rearwardly extending lower portion rigid with said inclined portion, and extensions carried by the free ends of said bracket portions respectively adapted to engage over the upper 30 edge of the side of a car and to rest against the outer face of the side of the car.

35 5. In combination with a car unloading hopper chute, brackets carried by said chute to detachably attach the latter to the side of a car, said brackets being extensible for adjusting the hopper toward or away from the

side of the car, each of said brackets further embodying an intermediate member having an upper inclined portion secured to 45 the bottom of the hopper, and a rearwardly extending lower portion rigid with said inclined portion, and extensions carried by the free ends of said bracket portions respectively adapted to engage over the upper 50 edge of the side of a car and to rest against the outer face of the side of the car, the extension of the inclined portion of the bracket having a series of apertures, and a removable pin adapted for selective reception 55 within the desired one of said apertures to engage the inner face of the side of the car for preventing displacement of the hopper away from the car and for permitting further adjustment of the upper end of the hopper toward or away from the side of the car.

6. A car unloading hopper chute embodying a bottom, a pair of sides, a cross piece rigidly connecting the sides above the bottom, a vertically swinging door having its 65 upper edge hinged to said cross piece, connecting rods disposed beside the sides of the hopper and having their outer ends pivoted to the door, a shaft journaled beneath the bottom of the hopper and having cranks 70 upon its ends pivotally connected to the inner ends of the connecting rods, a further crank rigid with said shaft intermediate the first named cranks, yieldable means connected to the last named crank and to the 75 bottom of the hopper for normally closing the door, a guide carried by the bottom of the hopper above said last named crank, and a flexible opening member for the door attached to said last named crank and passing 80 upwardly over said guide.

In testimony whereof I hereunto affix my signature.

MOSES L. TRIMMER.
